UNITED STATES PATENT OFFICE.

SAMUEL C. JUMP, OF DUBUQUE, IOWA.

RAILWAY TRACK.

Application filed August 2, 1922. Serial No. 579,096.

To all whom it may concern:

Be it known that I, SAMUEL CURTIS JUMP, a citizen of the United States, residing at Dubuque, county of Dubuque, State of Iowa, have invented a certain new and useful Improvement in Railway Tracks, and declare the following to be a full, clear, and exact description of the same, such as will enable others skilled in the art to which it pertains to make and use the same, reference being had to the accompanying drawings, which form a part of this specification.

At switching points in railway tracks, particularly the point where the frog is located, difficulty has always been experienced in maintaining the proper gauge between the various elements, effectively securing the rails and guard rails, and preventing looseness in and creeping of the frog.

The object of the present invention is to produce a simple and novel construction which will permit the wheel-supporting or wheel-engaging members of a track, particularly at a switching point, to be accurately located and firmly fixed in the first instance and thereafter to be maintained in proper working order for an indefinite length of time and without requiring constant supervision and adjustment.

The various features of novelty whereby my invention is characterized will herein-after be pointed out with particularity in the claims; but, for a full understanding of my invention and of its object and advantages, reference may be had to the following detailed description taken in connection with the accompanying drawings, wherein:

Figure 1 is a plan view of a section of a railway track where the frog occurs at a switching point;

Fig. 2 is a section on a somewhat larger scale, taken approximately on the line 2—2 of Fig. 1, all of the parts except the rail elements and the rail braces being shown in elevation;

Figs. 3, 4 and 5 are plan views, on a still larger scale, of the three sections into which one of the tie plates is divided;

Fig. 6 is a longitudinal section, on an enlarged scale, through the joint of two of the tie plate sections, shown as insulated from each other;

Fig. 7 is an edge view of the adjoining ends of two sections of the tie plate having associated therewith an adjusting spacer; and

Fig. 8 is a perspective view of the spacer employed in the construction shown in Fig. 7.

Referring first to Fig. 1, 1 represents the continuous rail in the main track, 2 the frog, and 3 the continuous rail in the turn-out track. A guard rail 4 is placed on the inner side of the rail 1 and a guard rail 5 is placed on the inner side of the rail 3. These track elements overlie long railroad ties 6 extending continuously underneath the same in the usual manner. In accordance with my invention I place on at least one of the ties, and preferably on three of them, a tie plate 70 extending continuously underneath the rails and the frog; these tie plates being indicated in Fig. 1 at A, B and C. Each tie plate is provided with integral shoulders projecting a short distance above the same 75 and across the entire width thereof at the following points: at 7 in position to abut against the outer edge of the base of the rail 1; at 8 in position to abut against the inner edge of the base of the guard rail 4; 80 at 9 and 10 in positions to abut against the base of the frog at opposite sides thereof; at 11 in position to abut against the inner side of the base of the guard rail 5; and at 12 in position to abut against the outer edge of 85 the base of the rail 3. Rail braces 13 and 14 are preferably placed on the inner sides of the two guard rails and the tie plate is preferably provided with two additional shoulders 15 and 16 abutting against the inner ends 90 or heels of the rail braces. Spikes, such as indicated at 17, may be driven through the tie plate on the outer sides of the rails 1 and 3, on the inner sides of the guard rails, and on opposite sides of the frog, the spikes 95 holding the rails, guard rails, and frog on the ties. Spikes may also be driven through the tie plates between each rail and its guard rail. The rail braces may be fastened in place by means of spikes or 100 screws 18 passing through the tie plate. Each tie plate may be spiked or screwed to the underlying tie at intermediate points as indicated at 19. If desired, each tie plate may be made in a plurality of sections arranged end to end and fastened together, thereby permitting the two rails of a track to be insulated from each other and providing means for adjustment. In the arrangement shown, each tie plate is made in three 110 sections bolted together by means of bolts 20.

The tie plates are made sufficiently heavy so that they will serve as efficient struts to transmit a lateral thrust from one track element, the guard rail 4, for example, directly through the tie plate and its shoulders to the other track elements lying in the direction of such thrust. The stresses starting at any one point will therefore be distributed throughout the entire structure and, as long as the various track elements lie in contact with the shoulders on the tie plates, there is no opportunity given for a shifting of the elements relatively to each other so as to produce a change in the gauge. Furthermore, since the frog decreases in width from the right hand end, as viewed in Fig. 1, to the left hand end, and since the shoulders 9 and 10 are shaped to lie parallel with the surfaces of the frog with which they engage, the frog may be said to rest in a tapered seat which will positively prevent creeping from the right toward the left as viewed in Fig. 1. The tie plates therefore serve as efficient anti-creepers to prevent the frog from traveling lengthwise in the direction which would cause harm. The tie plates of course protect the ties which, at the point in the track under consideration, ordinarily wear out very rapidly.

In Figs. 3, 4 and 5 I have illustrated the three sections of one of the tie plates, the section 21 being the one lying underneath the main rail 1, the section 22 lying beneath the frog, and the section 23 lying beneath the rail 3, as viewed in Fig. 1. The square holes in the plates in Figs. 3, 4 and 5 represent spike holes while the round holes and the elongated slots are for the purpose of receiving the bolts for fastening the sections together. The middle section 22 may be flat except that it has the raised shoulders 9 and 10 while each of the sections 21 and 23 has one end pressed upwardly through a height at least equal to the thickness of the middle section, as indicated at 24 and 25 respectively. The part 24 is adapted to overlie the left hand end of the section 22 and the part 25 is adapted to overlie the right hand end of the section 22. Bolts passing through the holes 26 in the part 24 and the slots 27 in the part 22 and through the holes 28 in the section 23 and the slots 29 in the section 22 serve to fasten the several sections together. If desired, a layer of insulating material, as indicated at 30 in Fig. 6 may be placed between the overlapping portions of two adjacent sections, sleeves or bushings of insulating material 31 being placed in the bolt holes.

If it be desired to provide means for adjusting the length of the plate, without leaving a gap between the edge of one section and the facing edge of the other section, Z-shaped plates, one of which is shown

at 32 in Figs. 7 and 8, may be provided, each of these plates having slots 33 adapted to register with the slots in the section 22 and having at the ends flanges 34 and 35 turned in opposite directions; the flange 35 being thicker than the flange 34. This plate may be placed between the overlapping ends of two sections as shown in Fig. 7. When the flange 35 is turned upwardly, the flange 34 is arranged between the facing ends or edges of the two sections and serves to transmit the thrust from one to the other. If it be desired to increase the effective length of the tie plate, the plate 32 can be reversed so as to bring the flange 35 in the position occupied by the flange 34 in Fig. 7; and, since the flange 35 is thicker than the flange 34, the effective length of the tie plate will be increased while maintaining continuity of metal throughout the length of the tie plate, thus avoiding the necessity of placing reliance on the grip of the bolts between the sections in order to transmit a thrust past a joint in the tie plate.

I claim:

1. The combination with the main rails, guard rails and turn-out rails and the frog of a railway track at a switching point, of tie plates extending continuously underneath and transversely of the same; each tie plate having thereon integral shoulders abutting against the outer side of each of said rails, against the inner sides of the guard rails, and on each side of the frog.

2. The combination with the main rails, guard rails and turn-out rails and the frog of a railway track at a switching point, of tie plates extending continuously underneath and transversely of the same; each tie plate having thereon integral shoulders abutting against the outer side of each of said rails, against the inner sides of the guard rails, and on each side of the frog; together with rail braces arranged above the tie plates on the inner sides of the guard rails.

3. The combination with the main rails, guard rails and turn-out rails and the frog of a railway track at a switching point, of tie plates extending continuously underneath and transversely of the same; each tie plate having thereon integral shoulders abutting against the outer side of each of said rails, against the inner sides of the guard rails, and on each side of the frog; together with rail braces arranged above the tie plates on the inner sides of the guard rails; said tie plates also having integral shoulders thereon abutting against the heels of the rail braces.

4. In a railway track, a frog, ties extending transversely underneath the frogs, tie plates arranged on said ties and secured thereto, each tie plate having thereon integral shoulders abutting against opposite sides of the frog, the spacing between the

shoulders being different on the different tie plates.

5. A tie plate comprising two members overlapped at their ends, and a Z-shaped adjusting plate comprising a web portion adapted to lie flat between the overlapping portions of the plate and short flanges ex-

tending in opposite directions from the web at the ends thereof, one of said flanges being thicker than the other. ¹⁰

In testimony whereof, I sign this specification.

SAMUEL C. JUMP.
